THROTTLE-VALVE FOR DRILLS.

1,373,853.

Specification of Letters Patent.

Patented Apr. 5, 1921.

Application filed October 11, 1918. Serial No. 257,788.

To all whom it may concern:

Be it known that we, LEWIS C. BAYLES and FRED M. SLATER, both citizens of the United States, residing at Easton, in the 5 county of Northampton and State of Pennsylvania, have invented a certain new and useful Improvement in Throttle-Valves for Drills, of which the following is a specification.

10 This invention relates to throttle valves and especially to throttle valves adapted to be used in connection with percussive hammer drills used in rock drilling.

The objects of the present invention are 15 to provide a throttle valve for a percussive hammer drill which has an independent motor for rotating the drill steel, which will permit the power delivered by the hammer to be varied and also the speed of rotation 20 of the steel to be varied throughout a wide range so that the speed of rotation may be varied while the hammer blow is maintained constant and also the hammer blow may be varied while the speed of rotation of the 25 steel is maintained constant. This is to permit a wide variation in the power delivered to each element so that different amounts of power can be supplied to either element relative to the other as is found best adapted 30 to the character of ground being drilled.

A further object is to provide a hammer drill in which rotation of the throttle handle and throttle valve to various positions permits the hammer to be used alone; that 35 is, while the drill is not being rotated; or the hammer operated lightly and the rotation varied; or the hammer and rotation both used at about one-half power; or the rotation used at full power and the hammer varied; or both elements used at full 40 power.

With these and other objects in view our invention consists in the features of construction and operation set forth in the following specification and illustrated in the accompanying drawings, forming a part 45 hereof, in which:

Figure 1 shows a percussive hammer, partly in section, showing the throttle valve 50 in position in the drill;

Figs. 2, 5, 8, 11 and 14 show cross sections through the throttle valve and casing with the throttle in different positions, taken on the line 2-2 of Fig. 1;

Figs. 3, 6, 9, 12 and 15, cross sections 55 through the throttle valve taken on the line 3-3 of Fig. 1; and

Figs. 4, 7, 10, 13, and 16, cross sections 60 through the throttle valve taken on the line 4-4 of Fig. 1.

Referring now more particularly to the figures of the drawing, 1 refers to the drill body of a conventional type of percussive hammer drill, provided with a casing 2 in which a throttle valve made in accordance 65 with the present invention is adapted to be contained and rotated. The throttle valve 3 is made in the form of a frustum of a cone as is usual in this form of throttle valve, the larger end having a fluid pressure recess 4 from which fluid is distributed to the different elements of the drill. Closing the larger end of the opening in the valve casing 2 is the valve plug 5 within which is contained the fluid nipple 6. The valve 70 3 at its smaller end is extended forming a shank 7 to which is attached the valve handle 8. As the action and function of the throttle valve will be better understood 75 from a study of Figs. 2 to 16, reference 80 will now be made to those figures.

In Figs. 2, 3, 4, which are sections taken on the lines 2-2, 3-3, and 4-4, respectively, of Fig. 1, are shown the positions of the openings extending from the central pressure chamber 4 to the periphery of the throttle controlling the admission of fluid to the fluid consuming elements of the drill which are in the example chosen for illustration, the hammer cylinder and the rotation motor. The opening also is shown for a lubricator, usually provided in this type of drill. Intercepting the valve recess in the casing 2 are the passages leading directly to the fluid consuming elements of the tool 85 respectively shown at 9 which leads to the hammer cylinder, 10 which leads to the rotating means, and the passage 11 which leads to the cavity in which the lubricator is located. The openings from the pressure 90 recess 4 to the periphery of the valve 3 are respectively in the plane of the throttle valve 3 intercepting the passages 9, 10, 11, above referred to. In alignment with the passage 9 are provided two openings of unequal width, respectively, 12 and 13, opposite each other so that when the throttle 95 is turned to the position shown in Figs. 5, 6

and 7 the smaller opening 12 permits a limited amount of fluid to pass sufficient to operate the hammer lightly which may be varied as seen in Fig. 5 by slightly varying 5 the position of the handle 8, and when the throttle is turned to the position shown in Fig. 14, a much larger amount may be passed, to operate the hammer at full power. The above arrangement permits a very wide 10 range of control over the power delivered by the hammer, as that is directly in proportion to the amount of fluid supplied to operate it. Furthermore, the throttle 3 may be rotated somewhat without any variation 15 in the hammer blow as when the position of the throttle is varied slightly up or down from the position shown in Fig. 8, in which position the fluid passed to the hammer cylinder is limited only by the size of the 20 opening 12 and the amount supplied to the rotating motor varied as is evident from an inspection of Fig. 10.

Similarly, the openings provided for passing the fluid from the recess 4 into the rotating motor are two in number and opposite each other. One of these is shown at 14 which is a relatively small opening and at 15 is a much larger opening subtending a much larger arc on the periphery of the 30 valve so that a constant supply of fluid may be supplied to the rotating motor during a large variation in the position of the throttle valve. A V-shaped slot 16 is cut in valve 3 intercepting the opening 14 so that the 35 amount of fluid passed through opening 14 into the rotating motor may be adjusted to a less amount than the full opening 14 would pass. (See Fig. 7.)

A single opening 19 connects the pressure 40 recess 4 with the lubricator and, as shown in Fig. 15, this opening 19 is open when the hammer and rotating motor are on full power. In no other position of the throttle valve, however, is this opening 19 in communication with the passage 11 leading to the lubricator.

Referring now more generally to the figures, Figs. 2, 3, 4, show the position of the throttle when all elements are closed off 50 from the supply of motive fluid.

Figs. 5, 6, 7, show the position of the throttle when the hammer alone is operating lightly. Slight variation of the throttle from this position has the effect of varying 55 the power of the hammer from zero up to the limited power permitted through the opening 12 and a further slight movement of the throttle increases the opening to the rotation up to the capacity of part 14.

60 In Figs. 8, 9, 10, the hammer is on at its limited or half power and the rotation is on very lightly, and variations from this position of the throttle may increase or decrease the power supplied to the rotating motor

without varying the power supplied the 65 hammer.

In Figs. 11, 12, 13, the rotation only is supplied with fluid at the maximum amount through the opening 15 and variation of the throttle to the position shown in Figs. 14, 70 15, 16, generally starts the hammer and finally brings its power up to its maximum. This is the most usual position during the operation of the drill and so for that reason the opening 19 is open to the lubricator in 75 this position of the throttle as shown in Fig. 15.

Further inspection of the figures of the drawing discloses that depression of the handle 8 from its closed position as shown 80 in Fig. 1 serves to first admit fluid to the hammer cylinder through the opening 12 and continued movement of the handle 8 in the same direction opens communication between the opening 14 and the rotation motor 85 so that with the handle in the position shown in Figs. 8, 9 and 10 the hammer is operated lightly and the rotation motor operated under about one half power. This 90 position of the handle and throttle may therefore be termed the "lazy" or reduced power position.

If on the other hand the throttle handle 8 is raised instead of being depressed the rotation motor is first started as clearly 95 shown in the Figs. 11, 12 and 13, and further rotation of the handle 8 to the position shown in Figs. 14, 15 and 16 admits full pressure fluid through the opening 13 operating the hammer at full power and 100 maintains the rotation motor at full power and also opens communication between the fluid recess 4 and the lubricator.

From the above it will be seen that a 105 throttle valve has been provided for percussive and rotating drills which will accommodate the elements to any type of rock being operated upon by varying either the hammer or rotating motor relatively to each other, or by maintaining one element constant while the other is varied, or both maintained constant and at a limited power, or both operated at full power.

It is to be understood that the present 115 showing and description disclose only one specific embodiment of our present invention and that other forms and modifications are included within the spirit and scope thereof, as expressed in the appended claims.

What we claim is:

1. In a throttle valve for percussive rock cutting tools having independent percussive and rotation elements, a valve casing, a valve rotatable therein, said valve having ports adapted to register with fluid conduits 125 extending to the fluid consuming elements of the tool, rotation of said valve in one direction being adapted to gradually vary

the supply to the conduit extending to the percussive element from nothing to light operating supply, and then maintain the supply to the percussive element uniform 5 while varying the supply to the rotation element.

2. In a throttle valve for percussive rock cutting tools having independent percussive and rotation elements, a valve casing, a valve 10 rotatable therein, said valve having ports adapted to register with fluid conduits extending to the fluid consuming elements of the tool, rotation of said valve in one direction being adapted to gradually vary the 15 supply to the conduit extending to the percussive element from nothing to light operating supply, and then maintain the supply to the percussive element uniform while varying the supply to the rotation element, 20 and rotation of said valve in the other direction being adapted to gradually open the supply to the rotation element until the supply is full open, and then maintain said supply full open, while gradually opening 25 the supply to the percussive element from nothing to full operating supply.

3. In a throttle valve for percussive rock

cutting tools having independent percussive and rotation elements, a valve casing, a valve rotatable therein, said valve having ports 30 adapted to register with fluid conduits extending to the fluid consuming elements of the tool, rotation of said valve in one direction being adapted to gradually vary the supply to the conduit extending to the percussive element from nothing to light operating supply, and then maintain the supply to the percussive element uniform while varying the supply to the rotation element, 35 and rotation of said valve in the other direction being adapted to gradually open the supply to the rotation element until the supply is full open, while gradually opening the supply to the percussive element from 40 nothing to full operating supply, said valve having a port communicating with an oil supply, which port is only opened when the supply to both the percussive and rotation elements are fully open. 45

In testimony whereof, we have hereunto set our hands.

LEWIS C. BAYLES.
FRED M. SLATER.
